US0D1050430S

(12) **United States Design Patent** (10) **Patent No.:** **US D1,050,430 S**
(45) **Date of Patent:** **** Nov. 5, 2024**

(54) **MEDICAL DEVICE**

(71) Applicant: **Aspivix SA**, Epalinges (CH)

(72) Inventors: **Mathieu Horras**, Basel (CH); **Julien Finci**, Lutry (CH); **David Finci**, Bernex (CH); **Lukasz Natkaniec**, Munich (DE)

(**) Term: **15 Years**

(21) Appl. No.: **35/513,992**

(22) Filed: **Oct. 6, 2021**

(80) **Hague Agreement Data**

Int. Filing Date: **Oct. 6, 2021**

Int. Reg. No.: **DM/218590**

Int. Reg. Date: **Oct. 6, 2021**

Int. Reg. Pub. Date: **Apr. 8, 2022**

(51) **LOC (14) Cl.** **24-02**

(52) **U.S. Cl.**

USPC **D24/141**

(58) **Field of Classification Search**
